(57) **CLAIM**

The ornamental design for a plant stand, as shown and described.

DESCRIPTION

FIG. 1 is a front perspective view of a plant stand according to the present invention;

FIG. 2 is a front elevational view thereof;

FIG. 3 is a side elevational view thereof, the opposite side being a mirror image thereof;

FIG. 4 rear elevational view thereof;

FIG. 5 is a top plan view thereof; and,

FIG. 6 is a bottom plan view thereof.

The broken lines in FIG. 3 are for illustrative purposes only and form no part of the claimed invention.
